(57) **CLAIM**

The ornamental appearance for a portion of a swivel elbow for a mask, as shown and described.

DESCRIPTION

FIG. 1 is a front view of a portion of a swivel elbow for a mask connector assembly according to our design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a rear perspective view thereof.

Where included, broken lines showing environment or structure are for illustrative purposes only and form no part of the claimed design.

Where included, dotted lines show the transition between claimed and unclaimed subject matter and form no part of the claimed design.
